UNITED STATES PATENT OFFICE.

THEODORE H. MULCH, OF NEW YORK, N. Y., AND OSCAR WIEDERHOLD,
OF SUMMIT, NEW JERSEY.

GAS-BURNER.

SPECIFICATION forming part of Letters Patent No. 621,840, dated March 28, 1899.

Application filed September 22, 1897. Serial No. 652,550. (No model.)

To all whom it may concern:

Be it known that we, THEODORE H. MULCH, a resident of the city, county, and State of New York, and OSCAR WIEDERHOLD, a resident of Summit, Union county, State of New Jersey, have invented certain new and useful Improvements in Gas-Burners, of which the following is a specification.

Our invention relates to gas-burners, more especially to Bunsen burners and incandescent gas-burners; and it consists in the construction hereinafter set forth and claimed.

Our invention will be understood by referring to the accompanying drawings, in which—

Figure 1 is a vertical section of a structure embodying our invention. Fig. 2 is an enlarged sectional view of the gas-inlet apparatus and the plug for regulating and controlling the flow of gas to the main burner. Fig. 3 is a plan view, partly in section, of the structure, Fig. 2, the section being taken on line 3 3 of Fig. 2. Fig. 4 is a section on line 4 4 of Fig. 2, looking upward. Fig. 5 is an exterior view of the burner proper with the burner-gallery, mantle, and mantle-supporting device removed; and Fig. 6 is a section on line 6 6 of Fig. 5, showing the air-shutter and its casing.

It will be understood that the burner is capable of use with any suitable gas or vapor.

Referring to the drawings, *a* is a gas-inlet plug bored axially at *b* for the passage of gas and provided with a valve seat or shoulder *c*, above which valve seat or shoulder the gas-inlet plug *a* is hollowed out and internally threaded for the reception of a threaded regulator-plug *d*. This regulator-plug *d* is provided with an axial passage *d'*, which feeds the pilot-light and communicates with the axial opening *b* in the gas-inlet plug at all times, so that the axial opening *b* in the gas-inlet plug will supply gas to the pilot-burner irrespective of the supply of gas to the main burner. Seated in or otherwise in communication with the passage *d'* is a pilot-burner *d''*, which extends upward through the burner and terminates within the periphery of the mantle at the point *d'''*. The function of this pilot-burner is well known. The gas-regulator plug *d* is likewise pierced with a plurality

of passages *d⁴*, shown in the present instance as three passages placed one hundred and twenty degrees apart and communicating with an equalizing-chamber *d⁵*, carried by the regulator-plug at the top or other convenient portion thereof. The top wall *d⁶* of the equalizing-chamber is perforated with a series of perforations *d⁷*, (shown most clearly in Fig. 3,) through which perforations the gas passes from the equalizing-chamber into an inner casing or mixing-chamber *e*, which is a continuous uninterrupted chamber, whose lower edge *e'* terminates at or near the top wall of the equalizing-chamber, so as to permit the inlet of air to the mixing-chamber from the outer casing air-chamber *f*. The air-chamber *f* is a continuous uninterrupted casing extending from the point of ignition of the burner-flame. This air-chamber *f* surrounds the mixing-chamber *e* and is preferably provided with a ring *f'*, which supports the mixing-chamber below the screen *g*, as will be explained.

The air-chamber *f* is closed and provided with perforations *f²* (best seen in Fig. 6) for the admission of air into the said air-chamber, which admission of air is regulated by an air-shutter *h*, shown in the present instance as a ring seated in the air-chamber and freely movable therein and provided with apertures registering with the apertures in the air-chamber at suitable times. The air-shutter *h* may likewise be provided with stops *h'*, which project through the apertures *f²* of the air-chamber and serve to limit the movement of the air-shutter in the mixing-chamber and has handles or abutments for receiving the thrust of the finger or tool for adjusting the position of the air-shutter, so as to close the openings in the air-chamber more or less when desired. The regulation and admission of gas to the burner are effected by manipulating the plug *d*. For this purpose the plug *d* is provided with an annular lip *d⁸*, which is adapted to rest upon the seat *c* of the gas-inlet plug *a* around the opening *b* therein, so that when the lip *d⁸* is firmly seated upon the seat *c* gas will pass only to the pilot-light. When, however, the plug *d⁸* has been turned by means of the handle *d⁹*, the lip *d⁸* is thereby lifted from its seat *c*, and gas can then flow to the main burner from the axial opening *b*,

under and around the lip d^8 , and through the passages d^4 into the equalizing-chamber d^5 , where the gas is distributed and allowed to pass through the apertures d^7 uniformly. The 5 gas then receives its mixture of air by reason of the air-current passing under the edge e' of the mixing-chamber, so that the air-and-gas mixture is made at the lower end of the mixing-chamber and passes upward through the said 10 mixing-chamber to the main burner, the air-and-gas mixture being heated by contact with the walls of the mixing-chamber and air-chamber, which receive heat from the burner, as will be well understood. The air comes to 15 the lower edge of the mixing-chamber in the following manner: It passes in through the apertures into the air-chamber and thence downward between the walls of the air-chamber and the mixing-chamber, which being 20 heated will superheat the said air during its descent, so that the air arrives at the lower edge of the mixing-chamber in a heated condition, where, as explained, it mixes with the gas and the mixture passes upward through 25 the mixing-chamber and is further heated.

The parts so far described constitute a Bunsen burner of a highly-improved type which may be used as an ordinary Bunsen burner or in conjunction with an incandescent mantle to constitute an incandescent gas-burner, the following-described construction being the preferable one: the air-chamber may be provided with a shoulder i , upon which a gallery j loosely rests, which gallery in turn supports a chimney-support k , shown in the present instance as an annular frame seated on a jog l of the gallery and provided with arms m , supporting a ring n , which closely hugs the upper end of the mixing-chamber of 35 the burner. The burner-gallery likewise supports a mantle-support o , from which a mantle p is suspended, which extends downward and closely hugs the ring n , which acts as an additional support for the mantle and 40 likewise to prevent the mantle from being displaced laterally by gusts of air or other causes. The lower ring k of the frame mentioned receives the lower edge of the chimney q , which chimney, as will be observed, 45 extends downward and, covering the apertures j^2 of the air-chamber, prevents air from blowing into the mixing-chamber in a horizontal current, so that in order to get to the apertures of the air-chamber the air must pass 50 upward through the perforations in the screen of the burner-gallery. Thus it will be observed that the air in order to reach the main burner must necessarily pass thereto in a very tortuous course, to wit: first, upward 55 through the burner-gallery and chimney to the apertures in the air-chamber, thence downwardly between the air-chamber and the mixing-chamber, and thence upwardly through the mixing-chamber to the burner, so that by 60 thus providing means for deflecting and diverting the air-current and bringing it to the burner-point in an extremely tortuous course

we are enabled to bring a great quantity of air to the burner without danger of flashing back or flickering, and thus get rid of the 70 necessity formerly existing of bringing air to the burner through restricted orifices and in small quantities. This large air-supply, as is well understood, will secure perfect combustion of the gas, so that all blackening 75 or defacing of the mantle by reason of carbon deposits on the mantle or otherwise will be obviated. This voluminous air-supply likewise enables us to use our lamp in high altitudes, even in places where heretofore 80 other lamps of standard makes could not be used. The gallery and the chimney-supporting frame and mantle-supports form in the present instance one rigid structure, which may be readily slid off the mixing-chamber 85 without disturbing the Bunsen flame. We attain this object principally by making the ring n and gallery of a proper diameter to slide on the air-chamber. We are also assisted in this object by a peculiar form of 90 sieve employed in our burner. Instead of providing an ordinary sieve carried by a ring fitting over the mixing-chamber, as has been usual heretofore and which would render it extremely inconvenient if not impossible for 95 us to slide the mantle-carrying and chimney-supporting devices over the mixing-chamber without disturbing the Bunsen flame, we provide a sieve g in the form of a sieve-basket, fitting into the mixing-chamber and not over 100 the mixing-chamber, so as to leave the exterior chamber of the mixing-chamber smooth and unbroken by any ring or other device for supporting the sieve. It will be obvious, however, that instead of forming the entire 105 sieve-basket with meshes we may provide a ring fitting into the mixing-chamber and carrying a sieve, the essential feature being that the exterior surface of the mixing-chamber shall present no obstruction to the 110 free movement up and down of the mantle and chimney supporting devices so as not to hinder the ready removal of the mantle and chimney from the burner without disturbing the Bunsen flame. It will likewise 115 be observed that the air-shutter is inaccessible from the outside of the burner unless the gallery and its adjunctive parts be lifted off the burner, so that the air-shutter once set cannot be reset except by lifting off the mantle and chimney, so that all danger of accidental closure of the air-shutter with its attended evils is obviated. It will likewise be observed that for the purpose of rotating the 120 gas-regulating plug so as to regulate the flow of gas to the light we have provided a pivoted sector r , provided with the usual pulls s , which sector gears with the lower edge of a toothed ring t , which surrounds the gas-plug and the lower end of the mixing-chamber 125 casing. We likewise provide means for regulating the flow of gas in the main orifice and in the by-pass or pilot-burner tube, which means are shown in the present instance as 130

a screw *u*, passing into the main gas-supply orifice *b*, and a screw *v*, passing into the axial opening in the gas-regulator plug which supplies the pilot-burner.

5. What we claim, and desire to secure by Letters Patent, is—

1. In an incandescent gas-burner, the combination with a mantle of a regenerative Bunsen burner comprising the following instrumentalities in operative combination, to wit: a continuous heat-conducting outer casing extending from the point of ignition of the Bunsen flame downward around the mixing-chamber and comprising the air-chamber of the burner, the said casing being directly heated by the Bunsen flame and being pierced below the point of ignition of the Bunsen flame with openings for the influx of air, an inner casing comprising the mixing-chamber adapted to deliver an air-and-gas mixture to the Bunsen flame receiving heat by conduction from the outer casing and extending downward within the outer casing and terminating at or near the bottom thereof, where-
25 by an annular air-passage is produced between the said chambers, means for closing the top of the said air-passage so as to form an annular chamber closed at the top and a gas-inlet arranged in proximity to the lower
30 end of the mixing-chamber and adapted to deliver gas thereto, whereby the outer and inner casings may be efficiently heated by heat conducted from the Bunsen flame so as to heat the air and the air-and-gas mixture, all
35 arranged so that the air will enter the apertures of the air-chamber, will pass downward through the air-passage and be efficiently heated and thence pass upward through the mixing-chamber to the Bunsen flame.
- 40 2. In an incandescent gas-burner, the combination with a mantle of a regenerative Bunsen burner, comprising the following instrumentalities in operative combination, to wit: the external continuous uninterrupted heat-conducting outer casing *f* comprising the air-chamber and receiving heat from the Bunsen flame, the continuous uninterrupted inner casing *e* comprising the mixing-chamber and receiving heat from the outer casing, the an-
45 nular partition *f'* intervening between the two chambers and closing the top of the an-
50 nular space between them and serving to conduct heat to the inner casing from the outer casing, the said outer casing being pierced at or
55 or near the said partition for the passage of air and the said inner casing extending downward into the outer casing to a point at or

near the bottom thereof and adapted to de-
50 liver an air-and-gas mixture to the Bunsen flame and a gas-inlet in proximity with the lower end of the chamber *e*, whereby the air will be compelled to pursue a tortuous course and will be heated by contact with the walls of the two casings, substantially as described and for the purposes set forth.

65 3. In a gas-burner, the combination with means for consuming gas, of an internally-screw-threaded sleeve, an externally-screw-threaded gas-regulator plug, the screw-threads of the plug and sleeve being in engagement, the said gas-regulator plug being provided with a passage therethrough normally open to allow gas to pass to a pilot-burner, the said plug being likewise passaged to conduct gas from a gas-inlet to a main burner, a seat co-
70 operating with the plug and means for producing a relative movement between the sleeve and plug to engage the seat and plug together.

75 4. In a gas-burner, the combination with means for consuming gas, of a screw-threaded gas-regulator plug provided with a passage therethrough normally open to allow the pas-
80 sage of gas to a pilot-burner, the said plug being likewise passaged to conduct gas from a gas-inlet to a main burner and a seat co-
85 operating with the plug and means for rotating the plug, whereby the plug will be brought into engagement with its seat.

90 5. In a gas-burner, the combination with means for consuming gas, of a gas-inlet pro-
95 vided with a seat, a rotatable screw-threaded plug co-operating with said seat and provided with a passage therethrough for conducting gas to a pilot-burner and likewise passaged for conducting gas from the gas-inlet to a main burner, and an equalizing-chamber carried by the rotatable plug and in communication with the main burner.

100 6. In a gas-burner, the combination of a gas-inlet, a seat, a rotatable screw-threaded plug apertured centrally for the passage of gas to a pilot-burner and likewise containing a plurality of passages around the said central passage, and means for rotating the said 105 plug whereby it may be brought against its seat and the flow of gas to the passages surrounding the central passage controlled.
